JOINT BREAKER AND CATHEAD

John H. Schreiber, St. Louis, Mo.

Application June 3, 1940, Serial No. 338,559

21 Claims. (Cl. 254—173)

This invention relates to joint breakers and catheads of the type adapted for breaking joints between pipe sections used in oil fields and elsewhere.

Objects of the invention are to provide an improved mechanism of the class generically disclosed in my copending application Serial No. 148,493, filed June 16, 1937, resulting in Patent No. 2,208,197, dated July 16, 1940, and embodying a novel combination and cooperative arrangement of the jerk line shoe on the operating drum to facilitate operation of the shoe by the drum and substantially eliminate friction between the shoe and the supporting frame or housing for the device; to provide novel means for supporting on the drum the actuator for the jerk line shoe to permit convenient removal and replacement of said actuator and the use in said supporting means and actuator of a hard metal or alloy to withstand the forces and impacts to which the device is subjected when in use; to provide an optionally operable device for adjusting or moving the actuator to a position in which it will engage the shoe during constant rotation of the drum and movement of the actuator therewith; to provide means for moving said device by the shoe during movement of the latter to the initial or unoperated position of said device, leaving the drum free to continue in rotation while the shoe is returned to its initial or unoperated position by operation of the jerk line; and to provide means for disengaging the actuator from the shoe about the time that the shoe moves said device to its initial position, thereby coordinating release of the actuator from the shoe with the disabling of said device.

Another object of the invention is to provide means for supporting the shoe in connection with the drum to permit swinging or pivotal movements or adjustments of the shoe and thereby prevent breaking of any of the windings or parts of the jerk line at its connection with the shoe, as occurs in devices in which pivotal adjustment of the shoe is not effected.

Another object of the invention is to provide an improved removable and replaceable support for the optionally operable device that adjusts or moves the actuator to a position for engaging the shoe during constant rotation of the drum.

Another object of the invention is to provide means for disabling the optionally operable device that adjusts or moves the actuator to engaging position automatically and as an incident to reverse turning movement of the drum.

Various other objects and advantages of the

invention will be apparent from the following description, reference being made to the annexed drawings, in which—

Fig. 1 is a sectional view of the housing parallel with the axis of the draw-works shaft, a portion of the drum and the actuator support mounted thereon also being in section.

Fig. 2 is a sectional view of the device transversely of the draw-works shaft.

Fig. 2^a is a sectional view showing the construction by which the optionally operable device for moving the actuator to effective position is disabled by reverse rotary movement of the drum.

Fig. 3 is a detail elevation of the device for adjusting or moving the actuator to a position in which it will engage the shoe, and also showing that part of said device which is engaged by the shoe during movement of the shoe by the actuator to return said device to its initial or unoperated position.

Fig. 4 is a side elevation of said device and the shoe actuator in position to be engaged with the shoe, a part of the supporting structure being in section.

Fig. 5 is a similar view showing the actuator engaged with the shoe.

Fig. 6 is an elevation similar to Fig. 3, showing the shoe in engagement with the shoe adjusting device which has been moved to its initial or unoperated position by the shoe.

Fig. 7 is a view showing the means for disengaging the shoe actuator from the shoe about the time that the shoe moves the actuator adjusting device to its initial or unoperated position.

Fig. 8 is a detail sectional view showing the removable and replaceable support for the shoe actuator and the means for pivotally supporting the shoe on the drum.

40 The stationary frame or housing 1 is generally of annular form, and has an end wall 2 formed with an integral cylindrical bearing or bearing race 3. This frame or housing may be rigidly secured to the draw-works by any appropriate

45 attaching means (not shown) with which the present invention is not concerned. A rotary element or drum 4 cooperates with the stationary housing to provide a space for enclosing parts of the present invention, and provided with an extension 5 for attachment to the draw-works shaft.

45 A bushing 6 is rigid with the element 4 and extends into the bearing race 3 and is supported by anti-friction bearings 7 mounted in said race.

50 The drum 4 is formed with a pair of integral

circumferential walls 8 having inwardly extended flanges 9 at their peripheries forming grooves 10 between said flanges and the periphery of the drum. The walls 8 at one side of the drum have gaps 11, and a recess is formed in the periphery of the drum having a bottom wall 12 (Fig. 8). A support comprising a base 13 adapted to seat in the recess in the periphery of the drum, and upon the wall 12, has arcuate walls 14 in continuation of the walls 8 and flanges 15 in continuation of the flanges 9. Therefore, when said support is attached to the drum by the fasteners 16, the gaps within the walls 8 and the flanges 9 are closed.

An actuator comprising a body 17 is mounted for rocking movements in the support 13 about an axis parallel with the axis of rotation of the drum. A notch 18 is formed in the actuator 17 and has a bottom wall 19, preferably formed on the same radius of curvature as the periphery of the drum 4. The body of the actuator 17 is cylindrical and its axis is approximately on or at the center of the arcuate wall 19 so that, when said actuator is turned to the position shown in Fig. 2, said wall 19 is in continuation of the peripheral wall of the drum; and, when said actuator is turned to the position shown in Fig. 8, the wall 19 is angularly disposed and the forward edge of the actuator 17 constitutes a shoulder extending beyond the periphery of the drum 4 far enough to engage the jerk line shoe during rotation of the drum 4.

The jerk line shoe 20 is mounted in the groove between the walls 8 and has a pair of lateral projections 21 engaging in the grooves 10. These projections 21 constitute pivotal supports for the shoe on the drum and permit the shoe to adjust itself so that it does not sharply bend the attached jerk line 22 at the end of the shoe. By the projections 21, the shoe is entirely supported by the drum during movement of the shoe by the drum, thus facilitating operation of the shoe and substantially eliminating friction between the shoe and the supporting frame or housing. When the shoe is at rest and in its initial or unoperated position, it is supported substantially out of engagement with the drum by an inclined flange 23 (Fig. 2) attached to a removable and replaceable plate 24 at the bottom of the housing or frame 1. In its initial or operated position, the shoe 20 is held against an abutment 25 and on the supporting flange 23 by a spring 26 mounted on the jerk line between the outer end of the stationary jerk line guide 27 and an abutment 28 attached to the jerk line (Fig. 2); and in this position, the projections 21 are substantially out of contact with the flanges 9, leaving the drum free to rotate without moving the jerk line shoe.

An arm 29 is rigid with one end of the actuator 17 and is adjacent to the side of one of the walls 14. A detent 30 is mounted in the free end of the arm 29 and actuated by a spring 31. The adjacent wall 14 has a pair of spaced recesses 32 and 33 (Figs. 2 and 5) adapted to be engaged by the detent 30. When the arm 29 is moved inwardly to extend the forward edge of the actuator 17 beyond the periphery of the drum 4, as in Fig. 8, the detent 30 is engaged within the recess 32, and will thereby retain the actuator 17 in said effective position for engagement with a shoulder 34 on the shoe 20; and, when said arm 29 is moved outwardly to turn the actuator 17 to a position in which the curved wall 19 is aligned with the peripheral wall of the drum 4,

the detent 30 is engaged in the recess 33. The contacting surfaces of the detent 30 and the recesses 32 and 33 are inclined so that the arm 29 may be moved from one position to another by application of pressure against a projection 35 on the free end of the arm 29. A cam 36 is attached to the wall 2 in a position to be engaged by the projection 35 when the arm 29 is latched in its inner position by engagement of the detent 30 in the recess 32 (Fig. 7).

As shown, the drum 4 is constantly rotating in a counter-clockwise direction (Fig. 7), the arm 29 extending rearwardly beyond the actuator 17. When the projection 35 engages the cam 36 during continued rotation of the drum, the arm 29 is forced outwardly to engage the detent 30 within the recess 33, thereby turning the actuator 17 to a position in which the outer wall 19 thereof is in alignment with the periphery of the drum 4. This will release the actuator 17 from the shoulder 34 on the shoe 20, leaving the said shoe free to be moved by the spring 26 to its initial or unoperated position on the flange 23 and against the abutment 25. In said position, the projections 21 of the shoe are substantially out of contact with the drum.

My invention comprises an optionally operable device for adjusting or moving the actuator 17 to a position in which it will engage the shoulder 34 during constant rotation of the drum and movement of the actuator therewith, and also means for moving said device to its initial or unoperated position by the shoe during movement of the latter, thereby leaving the drum 4 free to continue in rotation while the shoe is returned to its initial or unoperated position by the spring 26 and jerk line 22. The operation of the actuator 17 to disengage the shoe is timed so that said optionally operable device is moved to its initial or unoperated position by the shoe before the shoe is disengaged by said actuator. The said device comprises a unitary member 37 mounted on a pivot 38 supported by the plate 24. The member 37 is formed with a cam 39 and is operative to move said cam from the effective position shown in Fig. 3 to the ineffective position shown in Fig. 6, and vice versa. The cam 39 is adjacent to the periphery of one of the drum walls 8 and, when said cam is located in its effective position (Fig. 3), it will be engaged by the shoe 20 and moved thereby from said effective position to its ineffective position as shown in Fig. 6. The member 37 is formed with another cam 40 adapted to be engaged by the projection 35 and thereby move the arm 29 inwardly and thereby the actuator 17 to its effective position as shown in Fig. 8.

A rod 41 is supported for turning movements above the guide 27, and has an arm 42 attached to one end thereof adjacent to the member 37. A spring 43 has its upper end engaged in a spring seat in the underside of the arm 42 and its lower end seating upon an arm 44 projecting inwardly from the member 37 beyond the pivot 38. The spring 43 imparts upward pressure against the arm 44, thereby tending to move the member 37 inwardly to place the cam 40 in position to be engaged by the projection 35 and thereby turn the actuator 17 to the effective position shown in Fig. 8, in which position said actuator will engage the shoulder 34 of the shoe 20 and move said shoe along with the drum 4 and wind the line 22 on said drum. The shoe 20 adjusts itself pivotally upon the projections 21 so as to prevent any

angular bend of the line 22 at the end of the shoe 20. This is because the line 22 extends into a hole in the shoe 20, and said shoe adjusts itself so that the hole at the end of the shoe from which the line 22 extends is tangential to the adjacent peripheral surface of the drum. This prevents breaking of the strands of the jerk line, as would occur if there were an angular bend in the jerk line at the end of the shoe.

The shoe 20 is moved around with the drum until the projection 35 engages the cam 36 and at or about the same time the shoe engages the cam 39 and immediately moves said cam toward the right from the position shown in Fig. 3 to the position shown in Fig. 6, which is the position in which it will not be engaged by the projection 35. The lower end 45 of the cam 39 extends across the arm 42 and limits upward movement of said arm by the spring 43. A shoulder formation 46 on the lower edge of the cam 39 adjacent to the member 37 is arranged to engage over the arm 42 in the inward position of the member 37 (Fig. 3), thereby holding the arm 42 downward while the spring 43 holds the cams 39 and 40 in positions to be engaged by the shoe 20 and the projection 35, respectively. An arm 47 attached to the end of the rod 41 opposite from the arm 42 provides means for turning said rod 41 to move said arm 42 downwardly beyond the shoulder 46 and cause the spring 43 to move the member 37 inwardly toward the arm 42 and thereby place the cam 40 in position to be engaged by the projection 35 when said projection is carried around to the cam 40. The actuator 17 is thereby turned to its engaging position (Fig. 8) in which it will engage against the shoulder 34 on the shoe 20 and carry said shoe around with the drum. The shoe turns upon its supporting projections 21 to prevent sharp bending of the jerk line 22 adjacent to the shoe. When the shoe is carried around with the drum in this manner, it engages the cam 39 and forces the member 37 laterally away from the drum to a position in which the cam 40 will not be engaged by the projection 35. At or about the time that the member 37 is moved laterally by the shoe 20, the projection 35 engages the cam 36 and disengages the actuator 17 from the shoe, whereupon the spring 26 immediately acts to return the shoe to its initial or unoperated position upon the support 23 and against the abutment 25. Thus, the engagement of the actuator 17 with the shoe may be optionally effected and the disengagement thereof is automatically effected, and the parts are automatically restored to their initial or unoperated positions, leaving the drum free to rotate continuously without moving the shoe 20 until the rod 41 is again turned to cause inward swinging movement of the member 37.

One side of the housing 1 is formed with an opening 48 which is closed by a removable and replaceable plate 49 attached to the housing by fasteners 50. The opposite side of the housing 1 is provided with an opening 51 and a removable and replaceable closure plate 52 therefor. The plate 52 may support a high pressure lubricating fitting 53 for delivering lubricant into a passage 54 leading to the bearing 1.

The actuator 17 is held from axial displacement in one direction by contact of the arm 29 with the adjacent wall 14 of the actuator support; and is held from endwise displacement in the opposite direction by an extension 55 of the arm 29 engaging a flange 56 on said wall 14.

When the actuator support is apart from the drum, the arm 29 may be moved and the actuator 17 turned far enough to disengage the extension 55 from the flange 56 and permit withdrawal of the actuator from said support. When the device is in position on the drum, extent of such movement of the arm 29 and of such turning movement of the actuator 17 is limited by a formation 57 on the arm 29 contacting with the bearing race 3.

The drum 4 may be rotated in the reverse direction from that described and indicated by the arrow 58 (Fig. 5). Such reverse rotation of the drum will release the member 37 from latching engagement with the arm 42 and move said member outwardly from the position shown in Fig. 3 to its unoperated position as shown in Fig. 6. The member 37 is formed with a cam 59 which will be engaged by the projection 35 during reverse turning movement of the drum when the arm 29 is held in its outer position by engagement of the detent in the recess 33 and the member 37 occupies the position shown in Fig. 3. Such engagement of the projection 35 with the cam 59 moves the member 37 outwardly in opposition to the spring 43 to the position shown in Fig. 6, in which the shoulder formation 46 engages against the outer side of the arm 42. Thereafter, manual operation of the arm 47 is required to set the member 37 in its inwardly latched position in which the cam 40 will set the actuator 17 in position to engage the shoe shoulder 34 and the cam 39 in position to be engaged by the shoe, in the manner before described.

From the foregoing, it should be apparent that this invention attains all of its intended objects and purposes efficiently and satisfactorily. Friction between the shoe and other parts is reduced to a minimum, and the optionally adjustable device for moving the actuator 17 to effective position is also moved to ineffective position automatically and as an incident to operation of the shoe by the drum. The device may be varied as widely as the equivalent limits will permit without departure from the nature and principle of the invention.

I claim:

1. Mechanism of the character described comprising a rotary drum having a circumferential groove, a jerk line adapted to be wound on said drum within said groove, a shoe attached to said jerk line and extending into said groove, an actuator supported by said drum for movement relative thereto into a position for engaging and positively moving said shoe to wind said jerk line on said drum, means for moving said actuator to and from said position, and means for pivotally supporting said shoe on said drum to align said shoe and said jerk line.

2. Mechanism of the character described comprising a rotary drum, a jerk line adapted to be wound on said drum, a shoe attached to said jerk line, a device carried by and movable relative to said drum for engaging and moving said shoe in a direction to wind said jerk line on said drum, a member settable in a position to move said device relative to said drum to effect a driving engagement between said device and said shoe, and means operated by said shoe during movement thereof by said device for moving said member out of position to move said device to said engaging position.

3. Mechanism of the character described comprising a rotary drum, a jerk line adapted to be

wound on said drum, a shoe attached to said jerk line, an actuator supported by said drum for movement relative thereto into a position for engaging and positively moving said shoe to wind said jerk line on said drum, a member movable from and to a position to move said actuator into said position for engaging said shoe, and means for pivotally supporting said shoe in connection with said drum and alining said shoe and said jerk line during movement of said shoe by said actuator.

4. Mechanism of the character described comprising a rotary drum, a jerk line arranged to be wound on said drum, a shoe attached to said jerk line, a support detachably secured to said drum, an actuator movably mounted relative to said support and being removable from said drum with said support, a member for moving said actuator to a position to engage said shoe during rotation of said drum, and means operated by said shoe during movement thereof by said actuator for moving said member to a position in which it will not move said actuator.

5. Mechanism of the character described comprising a rotary drum having a circumferential groove, a jerk line adapted to be wound on said drum within said groove, a shoe attached to said jerk line, an actuator supported by said drum for movement relative thereto into a position for engaging and positively moving said shoe to wind said jerk line on said drum, parts for moving said actuator to and from said position, respectively, means for pivotally supporting said shoe on said drum to aline said shoe with said jerk line during movement of said shoe by said actuator, and means for supporting said shoe substantially out of engagement with said drum during rotation of said drum when said actuator is out of position for engagement with said shoe.

6. Mechanism of the character described comprising a rotary drum, a jerk line arranged to be wound on said drum, a shoe attached to said jerk line, means supported by said drum for movement relative thereto into a position for engaging and positively moving said shoe to wind said jerk line on said drum, means for pivotally supporting said shoe on said drum to aline said shoe and said jerk line and to prevent detachment of said shoe from said drum during movement of said shoe by said first named means, and a device for disengaging said first named means from said shoe.

7. Mechanism of the character described comprising a rotary drum, a jerk line adapted to be wound on said drum, a shoe attached to said jerk line, a device mounted on and movable relative to said drum for engaging and moving said shoe in a direction to wind said jerk line on said drum, means for pivotally supporting said shoe on said drum to aline said shoe and said jerk line during movement of said shoe by said device, and means for supporting said shoe in an unoperated position out of substantial engagement with said drum.

8. Mechanism of the character described comprising a rotary drum, a jerk line arranged to be wound on said drum, a shoe attached to said jerk line, a support detachably secured to said drum, an actuator movably mounted relative to said support for engaging and moving said shoe with said drum, a member for moving said actuator to a position to engage said shoe during rotation of said drum, an element for disengaging said actuator from said shoe, and means op-

erated by said shoe for moving said member from said position in which it moves said actuator.

9. Mechanism of the character described comprising a constantly rotating drum, a jerk line arranged to be wound directly on said drum, a shoe attached to said jerk line, an actuator mounted on said drum for movement relative thereto to engage and move said shoe to wind said jerk line on said drum, pivot means for supporting said shoe in connection with said drum, and a stationary support for holding said shoe normally out of substantial contact with said drum.

10. Mechanism of the character described comprising a rotary drum, a jerk line adapted to be wound on said drum, a shoe attached to said jerk line, an actuator supported by said drum for movement relative thereto into a position for engaging and positively moving said shoe to wind said jerk line on said drum, a cam for moving said actuator into said position, means for setting and retaining said cam in a position to move said actuator relative to said drum as aforesaid, and means for pivotally supporting said shoe on said drum to aline said shoe with said jerk line during movement of said shoe by said actuator.

11. Mechanism of the character described comprising a rotary drum, a jerk line adapted to be wound on said drum, a shoe attached to said jerk line, an actuator supported by said drum for movement relative thereto into a position for engaging and positively moving said shoe to wind said jerk line on said drum, a cam for moving said actuator into said position, means for setting and retaining said cam in a position to move said actuator relative to said drum as aforesaid, means for pivotally supporting said shoe on said drum to aline said shoe with said jerk line during movement of said shoe by said actuator, and a support for holding said shoe out of substantial engagement with said drum when said actuator is out of position to engage said shoe.

12. In a device of the character described, a stationary housing, a rotary drum mounted within said housing, a jerk line adapted to be wound on said drum, a shoe attached to said jerk line within said housing, means attached to said housing for supporting said shoe in an unoperated position substantially out of contact with said drum, an actuator supported by said drum for movement relative thereto to engage and move said shoe along with said drum to wind said jerk line on the drum, means for moving said actuator relative to said drum to position to engage said shoe, and means for pivotally supporting said shoe on said drum to aline said shoe with said jerk line during movement of said shoe by said actuator.

13. In a device of the character described, a stationary housing, a rotary drum within said housing, a jerk line adapted to be wound on said drum, a shoe attached to said jerk line, a detachable element supported by said housing for supporting said shoe in an unoperated position substantially out of engagement with said drum, an actuator mounted on and movable relative to said drum to and from position to engage said shoe and move said shoe along with said drum, a member for moving said actuator to position to engage said shoe during rotation of said drum, means for holding said member in an adjustment to move said actuator as aforesaid, and means operated by said shoe during movement thereof by said actuator for moving said member from said adjustment.

14. Mechanism of the character described

comprising a rotary drum, a jerk line adapted to be wound on said drum, a shoe attached to said jerk line and supported in an unoperated position substantially out of engagement with said drum, mechanism supported by said drum for movement relative thereto to engage and move said shoe along with said drum to wind said jerk line on the drum, and means for pivotally supporting said shoe on said drum to aline said shoe with said jerk line during movement of said shoe by said mechanism.

15. Mechanism of the character described comprising a rotary drum, a jerk line adapted to be wound on said drum, a shoe attached to said jerk line, a stationary support for holding said shoe substantially out of engagement with said drum during rotation of the latter, a device supported by said drum for movement to position to engage said shoe and move said shoe along with said device to wind said jerk line on said drum, optionally operative means apart from any mechanism that rotates said drum for moving said device to position to engage said shoe, and means for supporting said shoe on said drum to aline said shoe with said jerk line during movement of said shoe by said device.

16. Mechanism of the character described comprising a rotary drum, a jerk line adapted to be wound on said drum, a shoe attached to said jerk line, a stationary support for holding said shoe substantially out of engagement with said drum during rotation of the latter, a device supported by said drum for movement to position to engage said shoe and move said shoe along with said device to wind said jerk line on said drum, optionally operative means for moving said device relative to said drum to position to engage said shoe, interengageable parts on said shoe and drum for supporting said shoe on said drum to aline said shoe with said jerk line during movement of said shoe by said device, and a cam for disengaging said device from said shoe.

17. Mechanism of the character described comprising a stationary housing, a rotary drum in said housing, a detachable support in connection with said housing, a jerk line adapted to be wound on said drum, a shoe attached to said jerk line and normally held on said support by said jerk line, an actuator on said drum for movement relative to said drum to engage and operate said shoe to wind said jerk line on said drum, pivotal means for supporting said shoe on said drum to aline said shoe with said jerk line during movement of said shoe by said actuator, and mechanism mounted on said support for controlling engagement of said actuator with said shoe.

18. Mechanism of the character described comprising a stationary housing, a rotary drum

in said housing, a detachable support in connection with said housing, a jerk line adapted to be wound on said drum, a shoe attached to said jerk line and normally held on said support by said line, an actuator on said drum for engaging and operating said shoe to wind said jerk line on said drum, pivotal means for supporting said shoe on said drum to aline said shoe with said jerk line during movement of said shoe by said actuator, mechanism mounted on said support for controlling engagement of said actuator with said shoe, and means operated by the shoe during movement thereof by said actuator for restoring said mechanism to its unoperated position.

19. Mechanism of the character described comprising a rotary drum, a jerk line adapted to be wound directly on said drum, a shoe attached to said jerk line and unattached to said drum, a support for said shoe in its unoperated position, means movably mounted relative to the drum for engaging and moving said shoe to wind said jerk line directly on said drum, devices for pivotally engaging and supporting said shoe and alining said shoe with said jerk line during movement of said shoe by said means, and mechanism for moving said means relative to said drum to release said means from said shoe after a predetermined movement of said jerk line and said shoe with said drum.

20. Mechanism of the character described comprising a rotary drum, a jerk line adapted to be wound on said drum, a shoe attached to said jerk line, a support for said shoe in its unoperated position, means movably mounted relative to the drum for engaging and moving said shoe along with said drum to wind said jerk line on the drum, means for pivotally supporting said shoe on said drum during movement of said shoe by said means, and a device for moving said means relative to said drum and thereby releasing said means from said shoe after a predetermined movement of said shoe with said drum.

21. Mechanism of the character described comprising a rotary drum having a circumferential groove, a jerk line adapted to be wound on said drum within said groove, a shoe attached to said jerk line, a device carried by and movable relative to said drum for optional engagement with said shoe to move said shoe and wind said jerk line on said drum during constant rotation of the drum, projections on said shoe pivotally engaging said drum to aline said shoe and said jerk line and to prevent detachment of said shoe from said drum, and means for moving said device relative to said drum to disengage said device from said shoe.

JOHN H. SCHREIBER.
